FRONT PANEL FOR COOLER CABINET

Jacobus C. Van Rijn, Woodstock, N.Y.

Filed May 19, 1958, Ser. No. 50,943

Term of patent 14 years

(Cl. D62—4)

Fig. 1 is a perspective view of my front panel for cooler cabinet;

Fig. 2 is a top view; and

Fig. 3 is an end view.

I claim:

The ornamental design for a front panel for cooler cabinet, as shown.
